UNITED STATES PATENT OFFICE.

MAX RACHLIN, OF NEW YORK, N. Y.

GUTTER HANGER.

Application filed December 29, 1924. Serial No. 758,654.

To all whom it may concern:

Be it known that I, MAX RACHLIN, a citizen of Russia, and resident of the city of New York, in the county of Kings and State 5 of New York, have invented certain new and useful Improvements in Gutter Hangers, of which the following is a specification.

The present invention relates to improvements in gutter-hangers, that is to say to devices for supporting roof-gutters. The invention pertains more particularly to gutter-hangers for use with a gutter having a beaded edge, and including a bar portion 10 adapted to extend transversely between the upper edges of the gutter, said bar portion being provided at one of its ends with an arched portion designed to be bent around the bead of the gutter, and said arched portion being joined with a cradle portion 15 designed to underlie the gutter.

The main object of the invention is to provide a gutter-hanger of the type mentioned, having means to insure proper bending of the arched portion around and into snug engagement with the bead of the gutter and to insure a snug fit between the gutter and that section of the cradle portion which is adjacent the juncture of said arched 20 portion and said cradle portion.

With these and other objects in view, which will more fully appear as the nature of the invention is better understood, the same consists in the combination, arrangement and construction of parts hereinafter described, pointed out in the appended claims and illustrated in the accompanying drawings, it being understood that many changes may be made in the size and proportion of the several parts and details of construction within the scope of the appended claim, without departing from the spirit or sacrificing any of the advantages 25 of the invention.

One of the many possible embodiments of the invention is illustrated in the accompanying drawings, in which:—

Figure 1 is a side elevation of a gutter-hanger complete and ready for sale; Fig. 2 is a bottom plan view thereof; Fig. 3 is a side elevation of the hanger in the process of applying the same to a gutter, the latter being shown in section; Fig. 4 is a similar elevation of the hanger in position on a gutter; 30 and Fig. 5 is a side elevation, partly in sec-

tion, of a portion of the hanger, on a larger scale, applied to a gutter.

In the drawings, the numeral 10 indicates a roof-gutter, the outer edge of which is provided with a bead 11, as usual in constructions of this type, while its inner edge 12, adjacent the wall of the building, is plain. For supporting this gutter in proper relation to the roof of the building, there is provided a plurality of hangers, spaced apart a suitable distance, each of said hangers comprising a strap 13, which surrounds transversely the gutter, and a roof strap 14, attached to the strap 13 and the roof. The strap 13 is, preferably, made of a single 40 piece of sheet metal, and includes a rigid portion 15, preferably a channel bar, adapted to extend transversely between the upper edges of the gutter. On one end of this bar is formed an arched portion 16, that is designed to be bent around the bead of the gutter. This arched portion is initially of substantially semi-circular configuration, as appears from Fig. 1 of the drawings, it merging into a cradle portion 17, designed to underlie the gutter. The free end 18 of the cradle portion is adapted to be engaged with a slot 19 in a substantially U-shaped bend 20 on the opposite end of the strap 13, said bend being in engagement with the plain 45 edge of the gutter.

As appears from Fig. 1 of the drawings, the arched portion 16 and the cradle portion 17 are joined at an acute angle, and at the juncture of the said arched portion and said 50 cradle portion is formed, preferably by stamping, a projection 21 to stiffen said juncture.

The gutter-hanger is furnished to the trade in substantially flat state, as shown in 55 Figs. 1 and 2 of the drawings. When the hanger is to be applied to a gutter, the juncture between the arched portion 16 and the cradle portion 17 is first engaged with the free edge 22 of the gutter bead. The 60 hanger is then taken hold of by the comparatively rigid bar section 15, and the arched portion 16 bent around and into snug engagement with the bead of the gutter, the U-shaped bend 20 being then engaged with 65 the plain edge 12 of the gutter. The cradle portion 17 extends then downwards, as shown in Fig. 3 of the drawings. Thereafter the cradle portion is bent to underlie 70 the gutter, its free end being drawn through 75 105 110

the slot 19 in the bend 20 and bent against the latter, as clearly shown in Fig. 4 of the drawings. Inasmuch as the juncture of the cradle portion 16 and the arched portion 17 is relatively stiff and unyielding, proper bending of the arched portion around and into snug engagement with the bead of the gutter is insured. On the other hand, proper bending of the cradle portion around the body portion of the gutter is also insured, and this is aided by the fact that the arched portion and the cradle portion are bent initially at an acute angle to one another; that is to say at an angle at which the free edge portion of the bead and the adjacent portion of the gutter are disposed.

What I claim is:—

A gutter hanger for use with a gutter

having a beaded edge, including a rigid portion adapted to extend transversely between the upper edges of the gutter, an arched portion at one end of said rigid portion designed to snugly fit around the bead of the gutter, and a cradle portion joined with said arched portion designed to underlie the gutter, the free end of said cradle portion being adapted to be engaged with said rigid portion, said cradle portion extending at an acute angle in relation to said arched portion, before said arched portion is bent around the bead of the gutter.

Signed at New York, in the county of New York, and State of New York, this 23rd day of December, A. D. 1924.

MAX RACHLIN.
